THE SEPARATION OF PLUTONIUM FROM URANIUM AND FISSION PRODUCTS

George E. Boyd, Arthur W. Adamson, and Jack Schubert, Oak Ridge, Tenn., and Edwin R. Russell, Chicago, Ill., assignors to the United States of America as represented by the United States Atomic Energy Commission

Application August 29, 1944, Serial No. 551,734

7 Claims. (Cl. 23—14.5)

The invention relates to the separation of substances from each other, and more particularly relates to the separation of element 94 from substances of the kind present in the reaction mass resulting from neutron bombardment of uranium.

It is an object of the invention to provide a convenient process for separating substances of the kind present in neutron-irradiated uranium, that is, element 94, fission products, and uranium, from each other by successive steps of adsorption, such as chromatographic adsorption. Further objects will be apparent from the following description and the drawing appended thereto.

In the drawing, the sole figure is a schematic representation of a detailed process embodying the invention. The several tables contained herein further explain the invention as shown by the drawing.

In the following description, the isotope of element 93 having a mass of 239 is referred to as 93^{239} and the isotope of element 94, having a mass of 239 is referred to as 94^{239} . Element 94 may also be designated as plutonium, symbol Pu. Reference herein to any of the elements is to be understood as denoting the element generically, whether in its free state or in the form of a compound, unless indicated otherwise by the context.

Neutron-irradiated uranium may be prepared by reacting uranium with neutrons from any suitable neutron source.

Neutron irradiation of uranium produces $^{92}\text{U}^{239}$ which has a half-life of 23 minutes and by beta decay becomes 93^{239} . This element has a half-life of 2.3 days and by beta decay becomes 94^{239} . Neutron-irradiated uranium contains 93^{239} , 94^{239} and a large number of radioactive fission products produced by reaction of neutrons on fissionable atoms, such as ^{235}U which is present in uranium from natural sources. It also contains minor amounts of other products such as UX_1 and UX_2 . Inasmuch as the 93^{239} and 94^{239} content of neutron-irradiated uranium is produced in accordance with the neutron density of exposure multiplied by the time of exposure, and as the weight of radioactive fission products is proportional to the amounts of 93^{239} and 94^{239} formed, it is convenient to separate the desired elements when the combined amounts thereof are minute, such as, for example, approximately .02% by weight of the irradiated uranium. By storing the neutron-irradiated uranium for a suitable period of time, the 93^{239} is converted almost entirely to 94^{239} . Because the fission products in general are highly radioactive, it is preferred that these materials be removed.

The fission products consist of a large number of elements which may be classified into two groups; a light group with atomic numbers from 35 to 45; and a heavy group with atomic numbers from 51 to 60. The fission products with which we are particularly concerned are those having a half-life of more than three days since they remain in the neutron-irradiated reaction mass in substantial quantities at least one month after reaction. These products are chiefly radioactive isotopes of Sr, Y, Zr, Cb, and Ru of the group of atomic numbers from

2

35 to 45; and Te, I, Xe, Cs, Ba, La, and Ce of the group of atomic numbers from 51 to 60, inclusive.

The invention is based on the discovery that various substances, including plutonium, present in the neutron-irradiated uranium will be adsorbed by various adsorbents, and that they may be separated from each other or from foreign substances present by adsorbing one or more of the substances, successively removing the adsorbed substance or substances from the adsorbent, and collecting the removed material in substantially separate fractions. It is contemplated that the process will include a preliminary adsorption and desorption step in which the various substances will be partially or completely separated and subsequent adsorption and desorption steps in which partially separated substances are further isolated and purified. The plutonium, when referred to in the following description, is in its reduced or phosphate-insoluble state.

In the preliminary adsorption step as shown in the drawing, the reaction mass, resulting from the neutron bombardment of uranium (and containing plutonium, fission products, and uranium) is dissolved, as by nitric acid, and the solution S is flowed through an adsorbent contained in an elongated column 1. Since the solution contains two or more substances having different strengths of attraction for the adsorbent, the substances will be adsorbed in strata or layers. With many adsorbents, the order of adsorption and position of the adsorbed substance in the column is dependent upon the adsorption affinity of the particular adsorbate; the layers of adsorbates having higher adsorption affinities will, in the case of downward flow of solution through the adsorbent, be above the layers of those having lower adsorption affinities. Where two or more substances having different strengths of attraction for the adsorbent are treated, there will be a tendency for the substances to be adsorbed in strata or layers. Generally speaking, the order of adsorption and position of the adsorbed substance in a column of adsorbent is dependent upon the adsorption affinity of the particular adsorbate; the layers of adsorbates having higher adsorption affinities will, in the case of downward flow of solution through the adsorbent, be above the layers of those having lower adsorption affinities. This type of adsorption is known as chromatographic adsorption and, because of the nature and concentration of the substances present in neutron-irradiated uranium, is especially suitable for the separation of plutonium from the uranium and certain of the fission products.

If the original solution is passed for a considerable length of time through the adsorbent, the various strata of adsorbed material become progressively lowered in the case of downward flow of solution in the column. Thus, column 1 originally having an upper layer of adsorbed plutonium, a middle layer of fission products, and a lower layer of uranium, may soon consist substantially of layers of plutonium and fission products, and finally may contain only a single layer of plutonium. It is contemplated that advantages will result from carrying the process to any one of these three stages in obtaining the desired separation or removal of any one of the three substances mentioned, and consequently all such modifications are considered to come within the scope of the invention.

Such chromatographic adsorption for the separation of substances present in a solution of neutron-irradiated uranium may be carried out with a wide variety of adsorbents including, both inorganic adsorbents—such as silica gel and diatomaceous earth—and organic adsorbents—such as activated carbon, sulphonated carbonaceous material (zeo-carb), and phenol-formaldehyde resins preferably containing free sulphonic acid groups. Particu-

larly advantageous results are obtained in the first portion of the process by the use of ion exchange adsorbents, in which the cation of the adsorbent is exchanged for a similarly charged ion of the substance to be adsorbed. It has been found that the process is particularly effective when the adsorbent used is a relatively inert organic material containing sulphonic acid groups. Thus, the adsorbent may comprise phenol-formaldehyde resins, lignite, phenol-tannic acid resins, or the like, which contain numerous $R-SO_3-R'$ groups, in which R is an organic group and in which R' is hydrogen or a metal ion, although R' is preferably H^+ or Na^+ . A satisfactory adsorbent for use in column 1 is a phenol-formaldehyde condensation product containing such sulphonic acid groups. In the adsorption process, the hydrogen or other cation of the sulphonic acid group is replaced by a cation of the substance to be adsorbed and thereby forms a more or less loosely associated molecule with the residue.

The following is an example of a method by which a sulphonated resin may be prepared. One hundred and seventy-five parts of 1-hydroxybenzene-4-sulphonic acid are heated together with 40 parts of a formaldehyde solution of 30% strength for one-half hour to about 105° C. Then, further 60 parts of formaldehyde are added and the temperature is kept for about ten hours at 90° C. A hard black resin is formed which is stable to water and of conchoidal fracture. This resin is washed with water and ground to a powder. By regeneration with an acid or a solution of common salt, after use for adsorption, the base-exchanging body regains its original adsorption capacity.

It is preferred that the amount of adsorbent in column 1 should be in direct proportion to the quantity of uranyl nitrate hexahydrate solution to be run through the column. When plutonium is to be removed from uranium, fission products, and the like, it has been found desirable that for each pound of uranyl nitrate hexahydrate at least approximately 0.15 pound of the sulphonated phenol-formaldehyde resin be used. A proportion that has been found to be particularly suitable is 0.19 pound of the sulphonated phenol-formaldehyde resin for each pound of the uranyl nitrate hexahydrate.

The overall rate of adsorption of the plutonium, uranium, and fission products is generally dependent upon the particle size of the adsorbent in that more finely divided adsorbents will give an increased adsorption when the plutonium is in contact with the adsorbent for only a short period of time. Thus, a sulphonated phenol-formaldehyde resin of average particle size of 30 mesh will give only 75% adsorption as compared to the adsorption of 100-200 mesh resin when the plutonium is in contact with the adsorbent for ten minutes. When the time of contact is two hours, the difference between amounts adsorbed is negligible.

To facilitate the formation of layers or strata of adsorbed substances, column 1 is preferably of relatively small diameter or cross-section in proportion to its length. The bottom of the column is constructed to permit the passage of the solutions therethrough while retaining the adsorbent thereon. Tightly woven metal screens, glass wool, and the like may be employed for this purpose. The adsorbent is loosely packed in the column with its bed depth adjusted to the number and amounts of adsorbates in the solution to be treated. The particle size of the adsorbent is important in that the smaller the particle size, the more rapid the rate of adsorption, although the adsorbent must not be so fine as to greatly impede the rate of flow of the solutions through the column. When ion-exchange resins of the sulphonated phenol-formaldehyde type are used, a particle size of between 60 and 100 mesh has been found to be satisfactory.

To remove the adsorbates, one or more wash solutions A, B, and C are flowed through column 1 in such manner as to first remove the uranium, next the fission products, and then the plutonium. The removal is effected by the

adsorbates moving down the column in a continual process of desorption, readorption, and desorption with the wash solution or solutions. As the uranium is desorbed and passes down the column, the other adsorbates are also desorbed and likewise pass down the column, although at lesser rates. As each component reaches the bottom of the column, it passes out with the wash solutions and may be collected as a separate fraction.

The wash solutions A, B, or C contain cations exchangeable for the ions to be desorbed. It will be understood that they will be effective to remove adsorbate from the adsorbent until such time as substantial equilibrium is reached between the rates of desorption and readorption of the particular cation or cations being desorbed. While the dissolved adsorbate may be readSORBED along the column, further amounts of wash solution will again desorb the substances; this will continue until the adsorbate passes out of the column. In the case of plutonium, fission products, and uranium, it has been found that aqueous solutions of acids are particularly suitable because of the speed of desorption and the relatively small amounts of wash solution required, probably due to their high degree of dissociation. Aqueous solutions of acid-forming substances as, for example, mineral acids such as H_2SO_4 , HCl , or HNO_3 , or acid salts such as $NaHSO_4$, in varying concentrations have been used satisfactorily.

As some of the components present in the original solution may have similar adsorption affinities, one or more adsorbates, such as some of the fission products, 30 may overlap in the layers above and below any given layer. When such adsorbates are removed, the fraction containing any one adsorbate as the predominant adsorbed constituent may also contain moderate amounts of the adsorbates of the layers above and/or below. Thus, the 35 uranium fractions S' and A' may contain moderate amounts of fission products, the fission products fraction B' may contain a negligible amount of plutonium, and the plutonium fraction C' may contain moderate amounts of fission products.

To further separate and purify the partially separated substances, the various fractions obtained from column 1 may be treated with adsorbents. The uranium fraction will comprise the original solution S' from column 1 containing a substantial amount of unadsorbed uranium and the first wash solution A' containing a substantial amount of desorbed uranium. This uranium fraction is further treated in column 2. The fission products fraction B' requires no further treatment as it consists for the most part only of fission products. The plutonium fraction C' is further treated in column 3 to decontaminate the plutonium, that is, to remove radioactive fission products.

The uranium fraction consisting of fractions S' and A' 55 contains substantially all of the uranium, moderate amounts of fission products, and a negligible amount of plutonium. The uranium and fission products are separated from each other by passing fractions S' and A', either together or separately, through column 2 containing a cation exchange resin which may be similar to or different from that used in column 1. In column 2, the amount of adsorbent used may be increased considerably. It has been found that at least 1.02 pounds of adsorbent to 1 pound of the original uranyl nitrate hexahydrate solution is satisfactory. When 3.31 pounds of adsorbent is used, the flow rate is preferably 3.18 gallons per hour for each 0.34 square foot of bed area. Other conditions of adsorption in column 2 are similar to those of column 1.

As fractions S' and A' pass through the adsorbent, a substantial amount of the uranium is adsorbed with the remainder passing out of column 2 with the solutions which are collected as fraction SA''. Negligible amounts of "fission products having beta and gamma activity" referred to hereinafter as "beta activity" and "gamma ac-

tivity," for brevity) pass out of the column with the un-adsorbed uranium.

Column 2 is washed with an acid wash solution D which will remove substantially all of the adsorbed uranium together with negligible amounts of fission products to form fraction D'. Fractions SA" and D' containing substantially all of the purified uranium may be combined to form the final uranium fraction U.

A second acid wash solution E adapted primarily to remove fission products may be flowed through column 2 to remove moderate amounts of fission products from the adsorbent. Solution E with the desorbed fission products is collected as fraction E'.

The plutonium fraction obtained from the first adsorption step contains substantially all of the plutonium together with moderate amounts of fission products. To further separate and purify the plutonium, solution C' is flowed through column 3 containing an adsorbent whose anion forms insoluble surface compounds with the plutonium. Such adsorbents comprise compounds of low solubility having a monomeric or soluble anion and include zirconium phosphate and barium iodate. The plutonium may be recovered using other adsorbents such as zeolites, that is, for example, sodium aluminum silicate, sodium titanium silicate, and sodium-zirconium silicate, and, if sulphonated resins are used in column 1, phenol-formaldehyde resins containing a greater number of sulphonated acid groups than the ion exchange resins used in column 1. Of these, zirconium phosphate is very satisfactory when used in column 3 in the approximate ratio of 0.0027 pound for each pound of the original uranyl nitrate hexahydrate in the solution S. Where 4 grams of zirconium phosphate is used, the rate of flow of solution C' is preferably from 30 to 35 ml. per minute for each 38 cm.² of bed area.

As an example of one method of preparation of the zirconium phosphate, a zirconium salt solution, for example, a solution containing zirconium nitrate, is added to an excess of phosphoric acid thereby obtaining a precipitate containing zirconium phosphate. To insure against the presence of zirconyl phosphate in the precipitate, it is preferred to digest the precipitate in the presence of nitric acid, for example, in a solution being between 2 M and 4 M in HNO₃, at 90° C. to 100° C. for approximately one hour to convert the zirconyl phosphate to zirconium phosphate. When it is desired to obtain the zirconium phosphate on an inert supporting material such as glass wool, silicates, powdered glass, the digestion of the initial precipitate to convert substantially all of this precipitate to zirconium phosphate may be done in the presence of the inert supporting material thereby causing the zirconium phosphate to adhere firmly to such inert supporting material.

As solution C' flows through the zirconium phosphate column, substantially all of the plutonium is adsorbed while most of the fission products pass through the adsorbent and out of the column; they may be collected as fraction C''. An acid wash solution F adapted primarily to remove fission products is passed through column 3 to remove as much of the adsorbed fission products as possible and is then collected as fraction F'. The two fractions C'' and F' constitute the fission products fraction from the zirconium phosphate column. To remove the plutonium, wash solution G consisting of a single acid and adapted primarily to remove plutonium is passed through the column; it removes substantially all of the plutonium together with negligible amounts of fission products to form fraction Pu.

Fission products fractions E', B', C'' and F' may be combined to form the final fission products fraction FP. Plutonium fraction Pu from column 3 contains substantially all of the purified plutonium.

In one embodiment of the invention neutron-irradiated uranium is dissolved in nitric acid to form solution S

which is a 10% solution of uranyl nitrate hexahydrate having a pH value of between 1 and 3.

Solution S, in the amount of 42 liters, is flowed through a finely divided adsorbent contained in cylindrical column 1 which is approximately 7 cm. in diameter and 13 cm. in length. The adsorbent is a cation exchange resin of the sulphonated phenol-formaldehyde type. For the adsorption in column 1, the amount of resin used is preferably 0.22 pound for each pound of the uranyl nitrate hexahydrate in the solution to be treated; for 42 liters of solution, 2.07 lbs. of adsorbent is used. The 42 liters of solution S are flowed through the column by gravity at an approximate rate of 30 ml. per minute.

As the solution passes through the adsorbent, substantially all of the plutonium, most of the fission products, and a small amount of the uranium are adsorbed. A large amount of the uranium is not adsorbed in the column but passes out with the solution to form fraction S'.

To remove the adsorbed uranium, wash solution A comprising 0.25 M H₂SO₄ in the amount of 9.6 liters is flowed through the column. The wash solution A removes the adsorbed uranyl and carries it out of the column to form fraction A'. As the uranium is desorbed by solution A, the other layers of adsorbates are also desorbed and are moved down the column.

Fractions S' and A' contain substantially all of the uranium present in solution S together with moderate amounts of fission products and a negligible amount of plutonium. These fractions are set aside for later treatment to further separate the uranium from the fission products present.

To remove fission products from column 1, wash solution B comprising 7.15 liters of a solution which is 0.6 M in H₃PO₄ and 1.0 M in HNO₃ is flowed through column 1. A moderate amount of fission products is removed by solution B together with a minute amount of plutonium to form fraction B'. Fraction B' may be considered as the fission products fraction of column 1.

To remove the plutonium, wash solution C comprising 11.8 liters of a solution which is 0.8 M in H₃PO₄ and 1 M in HNO₃ is flowed through column 1. Substantially all of the plutonium is removed by wash solution C together with moderate amounts of fission products to form fraction C'. Fraction C' may be considered as a plutonium fraction of column 1 and is reserved for further treatment to separate the plutonium from the fission products present.

To further separate the uranium from the fission products present in the uranium fractions S' and A', these fractions are flowed through column 2 containing an adsorbent similar to that used in column 1. For column 2, the amount of resin used may be increased; one pound of the sulphonated phenol-formaldehyde resin for each pound of original uranyl nitrate hexahydrate in the solution has been found to be suitable. Column 2 has a diameter of 20 cm. and a length of 10 cm. and contains 1.5 kg. of adsorbent.

Fractions S' and A' are separately flowed through column 2 at a rate of 200 ml. per minute. A substantial amount of uranium is adsorbed while the remainder, together with a minute amount of fission products, passes out of the column with the solution to form fraction SA".

To remove the adsorbed uranium from column 2, wash solution D comprising 35 liters of 0.25 M H₂SO₄ is flowed through the column. Wash solution D removes substantially all of the adsorbed uranium together with minute amounts of fission products to form fraction D'. Fraction SA" and fraction D' constitute the purified uranium fraction as they contain substantially all of the uranium that was present in the original solution S, no plutonium, and only minute amounts of fission products.

To remove as much of the adsorbed fission products

from column 2 as possible, wash solution E comprising 42 liters of 6 M HNO_3 is flowed through the column; it removes moderate amounts of fission products to constitute fraction E', the fission products of fraction of column 2.

The plutonium fraction C' from column 1 is further treated to separate the plutonium from the moderate amounts of fission products present by flowing it through column 3. The cylindrical column 3 is preferably 7 cm. in diameter and 8.5 cm. in length and contains 0.004 kg. of zirconium phosphate. Fraction C' is flowed through the adsorbent at a rate of 33 ml. per minute during which time substantially all of the plutonium is adsorbed together with moderate amounts of fission products. The unadsorbed fission products pass out of the column with the solution to form fraction C''.

To remove the adsorbed fission products from column 3, wash solution F comprising 3.3 liters of a solution which is 0.1 M in H_3PO_4 and 2 M in HNO_3 is flowed through the column. Wash solution F removes the minute amounts of fission products to form fraction F'. Fractions C' and F' contain the fission products from column 3.

To remove the adsorbed plutonium from column 3, wash solution G comprising 5.8 liters of 7 M HNO_3 is flowed through the column. Substantially all of the plutonium is removed together with very small amounts of fission products to form fraction Pu.

If desired, the step of removing fission products from column 1 as a separate fraction B' may be omitted. In such case, the fission products that would otherwise be removed by wash solution B pass out of column 1 with wash solution C and are contained in fraction C'. They are separated from the plutonium in column 3. Where use of wash solution B is omitted, the composition of wash solution C is preferably changed from a solution 0.8 M in H_3PO_4 and 1 M in HNO_3 to a solution 0.2 M in H_3PO_4 and 2 M in HNO_3 .

The various solutions and their approximate composition with reference to the drawing are summarized in the following tables. The percentages given in Tables II to VI are in terms of the respective materials contained in the original uranyl nitrate hexahydrate solution.

Table I

	Order of Flow thru Column #1	Solution	Quantity of solution, liters
S.....	1st.....	$UO_2(NO_3)_3 + f. p. + Pu + HNO_3$	42.00
A.....	2nd.....	0.25M in H_2SO_4	9.6

Various amounts of the plutonium, uranium, and fission products remain adsorbed on the adsorbents in columns after the desorbing solutions have been flowed through the columns, this being particularly true where freshly prepared columns are used. Such retention of adsorbates from previous operations does not substantially affect the adsorption characteristics of the adsorbent in the columns with respect to plutonium, uranium, and fission products to be later treated.

The above detailed description has been given for purposes of illustration and it is to be understood that the invention is to be limited only by the scope of the appended claims.

We claim:

1. The method of separating plutonium from beta- and gamma-active fission products and uranium in solution containing ions of a compound of plutonium in which the plutonium ions are in a tetravalent state and ions of compounds of beta- and gamma-active fission products and uranium which comprises contacting said solution with a phenol-formaldehyde cation exchange resin adsorbent to selectively adsorb said plutonium ions and at least a portion of said fission products including gamma-active fission products leaving a substantial portion of ions of fission products and uranium in solution, then removing the solution from the cation exchange resin adsorbent and the adsorbed plutonium and fission products, thereafter forming another solution containing ions of plutonium and gamma-active fission products by redissolving the adsorbed fission products and plutonium from the cation exchange resin adsorbent with nitric acid, and then contacting the resultant solution with a zirconium phosphate adsorbent whereby said plutonium ions

are preferentially adsorbed from solution leaving ions of gamma-active fission products in solution.

2. A process of isolating plutonium values from a feed solution containing said plutonium values in a maximum valence state of +4 together with uranium values and fission product values, comprising contacting said solution with a first adsorbent selected from the group consisting of phenol-formaldehyde resin, sulphonated phenol-formaldehyde resin, phenol-tannic acid resin, lignite, silica gel and diatomaceous earth, whereby said plutonium values and part of said fission product values are adsorbed while said other part of said fission product values and the uranium values remain in solution; separating said adsorbent from said solution; contacting said adsorbent with an inorganic acid selected from the group consisting of sulfuric acid, hydrochloric acid, nitric acid, a dilute mixture of phosphoric and nitric acids and sodium bisulfate, whereby an eluate is formed containing said plutonium and said fission product values previously held by said adsorbent; contacting said eluate with a second adsorbent selected from the group consisting of zirconium phosphate, barium iodate, sodium aluminum silicate zeolite, sodium titanium silicate zeolite, sodium zirconium silicate zeolite and sulphonated phenol-formaldehyde resin having a higher degree of sulphonation than sulphonated phenol-formaldehyde resin used as said first adsorbent, whereby said plutonium values are preferentially adsorbed while most of said fission products remain in solution; and removing said plutonium from said second adsorbent by contacting with a mineral acid.

3. The process of claim 2 wherein said feed solution is a nitric acid solution.

4. The process of claim 2 wherein said first adsorbent is a sulphonated phenol-formaldehyde resin and said second adsorbent is a sulphonated phenol-formaldehyde resin having a higher degree of sulphonation than said first adsorbent.

5. The process of claim 2 wherein said first adsorbent is sulphonated phenol-formaldehyde resin, the inorganic acid for elution of said plutonium values and said fission product values from said first adsorbent is a dilute mixture of phosphoric and nitric acids, said second adsorbent is zirconium phosphate and the acid for removing the plutonium values from the zirconium phosphate is nitric acid.

6. The process of claim 5 wherein the nitric acid for elution of the plutonium values from the zirconium phosphate has a concentration of about 7 M.

7. A process of separating plutonium values present in a maximum valence state of +4 in a nitric acid solution of neutron-irradiated uranium together with fission product and uranium values, comprising contacting said nitric acid solution with a sulphonated phenol-formaldehyde resin, whereby said plutonium values, part of said fission product values and a minor fraction of said uranium values are adsorbed on said resin; washing the resin with dilute sulfuric acid whereby said adsorbed uranium values are removed from said resin; contacting said resin with a dilute mixture of phosphoric and nitric acids whereby the bulk of said adsorbed fission product values are removed from said resin; contacting said resin with a further quantity of a dilute mixture of phosphoric and nitric acids whereby an eluate containing said remaining fission product values and plutonium values is obtained; passing said eluate containing the plutonium and fission product values through zirconium phosphate whereby said plutonium values are held by the zirconium phosphate while most of the fission product values remain in solution; contacting said zirconium phosphate with a dilute mixture of phosphoric and nitric acids whereby the adsorbed fission product values are removed from the zirconium phosphate; and contacting said zirconium phosphate with nitric acid of a concentration of about 7 M whereby said plutonium values are removed from the zirconium phosphate.
